Fig. 8.

A = Angular length of each circular arc in degrees.

R = Radius of major circular arc.

r = Radius of minor circular arc.

R_m = Radius at $\frac{360}{2n}$ degrees to a radial line bisecting either adjacent circular arc.

R_L = Radius at L degrees from end of large circular arc.

r_L = Radius at L degrees from end of small circular arc.

n = Number of major arcs or number of minor arcs.

$R_m = \frac{R+r}{2}$

$R_L = R - \frac{R - R_m}{\left(\frac{360 - A}{n * 2L}\right)^2}$

$R+r = R_L + r_L$

$r_L = r + \frac{R - R_m}{\left(\frac{360 - A}{n * 2L}\right)^2}$

PUMPS AND MOTORS

Charles Scott Prendergast, Eashing, England, assignor of one-half to Hamilton Gordon, Weyburn, Elstead, Surrey, England

Application March 5, 1954, Serial No. 414,422

1 Claim. (Cl. 103—4)

This invention relates broadly to pumps and motors and more particularly to an improved rotary pump or motor of the kind having a series of stator chambers, a series of phase-displaced rotors one in each stator chamber, and movable abutments between the stator chambers and the rotors, and wherein the stator chambers and the rotors are relatively profiled to bring about reciprocal rates of acceleration and deceleration of the movable abutments as the rotors rotate, whereby the total instant fluid displacement of the series is practically uniform.

One of the objects of the invention is to provide a construction of rotary pump or motor having a high degree of efficiency and reliability.

Another object of the invention is to provide a construction of rotor for rotary pumps or motors which is formed on predetermined contours including interconnected curves, one portion of which operates in coaction with associated parts of the rotor pump or motor at a predetermined rate of acceleration, which may be constant, and another portion of which operates in association with the said parts of the rotary pump or motor at a reciprocal rate of deceleration.

A further object of the invention is to provide a new and improved rotary pump or motor, of the movable abutment type, comprising a series of stator chambers with a series of rotors phase-displaced, there being one rotor to each stator chamber, and movable abutments, diametrically opposed, contained between each stator chamber and rotor, inlet and discharge ports on either side of each abutment being isolated from each other by sealing contact of the abutments with the stator and rotor.

This invention is a development of that disclosed in the specification of U. S. Patent 2,609,754, and a further object is to modify and adapt the principle of that patent specification to provide a device of the class described in which the perimeter of each rotor is formed with an even number not less than four of equal arcs of major radius and with a corresponding number of equal arcs of minor radius, each arc of major radius joined to an adjacent arc of minor radius by a curve determined according to mathematical formulae for insuring mass production of the rotors at relatively low cost and for obtaining reliable and uniform operation of pumps or motors in a large production program as set forth more fully in the specification hereinafter following by reference to the accompanying drawings, in which:

Figure 1 is a vertical longitudinal sectional view through a fragmentary portion of a multiple chamber pump embodying the invention, the view being taken on line I—I of Fig. 2; Fig. 2 is a transverse sectional view taken on the line II—II of Fig. 1; Fig. 3 is a transverse sectional view taken on line III—III of Fig. 1; Fig. 4 is a fragmentary longitudinal sectional view taken on line IV—IV of Fig. 2; Fig. 5 is a fragmentary longitudinal sectional view taken on the line V—V of Fig. 2; Fig. 6 is a view of one of the identical rotors in the rotary pump or motor in this invention; Fig. 7 is a curve diagram illustrating the compounded flow displacement controlled by the rotors of the rotary pump or motor illustrated in Figs. 1—6 and Fig. 8 is a diagram showing the manner of

2

laying out the curve contours for the rotor in accordance with the principles of the invention.

Referring to Figs. 1 to 6 reference character 1 indicates a shaft journalled in end housings 2 and 3 of the fluid casing, the shaft having keyed thereon in the illustrated embodiment two similar rotors 4 (of special profile hereinafter particularly described) phase-displaced at 90 degrees and surrounded by stator elements 5. Spacer plate 6 separates one stator and rotor from the other 10 stator and rotor while the housing members, which include liners 7, contain them at the ends. The described parts are held assembled by bolts 9, shown in the cross sectional views Figs. 2 and 3, but omitted from the longitudinal sectional views for the sake of clearness which 15 pass through holes formed through the end housings 2, 3, the liners 7 and stator element 5, and the spacer 6. The bore of each stator element is cylindrical in shape.

Each of the two stator elements has two diametrically opposed abutments 10 which slide in radially extended 20 recesses 11 in the stator elements, the recesses in one stator coinciding radially and circumferentially with the recesses in the other stator and disposed in a plane extending through the shaft 1. The outer ends of the recesses in one stator are connected to the outer ends of the 25 recesses in the other stator by means of holes 12A through the spacer member 6. Slots 12 in the rear of the abutments connect the outer ends of the recesses to the bore of the stator. These sliding abutments bear constantly on the perimeters of the rotors under fluid pressure 30 on their outer end surfaces. Owing to the special form of the phase-displaced rotors the fluid pressure remains constant as the fluid displaced by one pair of abutments moving outwards is at all times exactly absorbed by the aligned pair of abutments moving inwards, by means of 35 holes 12A in the spacer plate 6. Initial pressure at the outer ends of the abutments is obtained through slots 12 in the rear of the abutments 10. If desired slots 12 can be omitted as initial pressure can be obtained through the sliding clearance allowed for the abutments in the 40 recesses.

Extending diametrically into the end housing member 3 is a fluid inlet duct 13 shown more particularly in Figs. 2 and 4 which communicates with two sets of aligned holes in the said end member 3, the liner 7, the 45 stators 5, and the spacers 6, these aligned holes forming two diametrically opposed fluid inlet passages 14 each of which opens radially into the stator chambers in advance of the sliding abutments in respect to the rotation of the shaft 1. Also extending diametrically into the housing member 3, as shown in Figs. 2 and 5, is a fluid discharge duct 15 which communicates with two diametrically opposed fluid outlet passages 16 each of which communicates radially with the stator chambers 55 in the rear of the sliding abutments.

It will be understood that since each rotor 4 coacts with two sliding abutments 10, each of which is disposed between a fluid inlet 14 and a fluid outlet 16, two identical displacement capacities are afforded in each stator, each of which capacities is swept twice during one revolution of the rotor. Such an arrangement has the advantage that it automatically provides hydraulic balance of each rotor and consequently of the driving shaft.

The perimeter of each rotor is formed by four or a greater equal number of major and minor arcs, as shown 65 at *a* and *b* in Fig. 6, all arcs being subtended by equal angles of less than 90 degrees. Joining curves *c*, connecting adjacent major and minor arcs *a* and *b* and forming a smooth junction with each arc, complete the perimeter. The radii of the major arcs are each almost equal to the radius of the stator chamber, the difference between them being sufficient to allow for running clearance. The radii of the minor arcs are smaller than the radii 70

3

of the major arcs by a predetermined amount, this amount being a governing factor in the cubic capacity of the pump or motor. The radius of a joining curve at the point mid-way between adjacent major and minor arcs is the mean of the radius of the major arc and the radius of the minor arc. The radii of the remainder of the joining curve can be determined as follows: The difference between the radius of a major arc and any radius of the joining curve between the adjacent end of the major arc and the mid-way point of the joining curve varies with the square of the angle contained between the radius and the junction point of the joining curve and the major arc. For example, if this difference is D at one degree from the end of the major arc, it should be $4 \times D$ at two degrees from the end of the major arc, and $9 \times D$ at three degrees from the end of the major arc. The difference between any radius r of the joining curve and the radius of a minor arc between the midway point of the joining curve and the adjacent end of the minor arc varies with the square of the angle contained between the radius r , and the radius at the junction point of the joining curve and the minor arc. For example, if this difference is d at one degree from the end of the minor arc, it should be $4 \times d$ at two degrees from the end of the minor arc and $9 \times d$ at three degrees from the end of the minor arc. If this is followed in profiling the rotors 4, the abutments 10 in contact with the rotors will travel outwards for the first half of their movement at a constant rate of acceleration and for the second half of their movement at a constant rate of deceleration. During the same periods the aligned abutments in contact with the other rotor will travel inwards for the first half of their movement at a constant rate of acceleration and for the second half of their movement at a constant rate of deceleration. These exactly reciprocal rates of movement determine that the fluid displacement of an abutment when moving outwards is at all times equal to the fluid absorption of an abutment moving inwards, thus ensuring continuous contact at all times between the abutments and the rotors. Having provided continuous contact between the abutments and the rotors by this form of profile it is found that the combined instant displacement produced by rotation of the two complementary rotors is practically constant.

Fig. 7 shows the characteristic curves for the compounded flow of two coaxing rotors.

In Fig. 8 we have shown the manner of laying out the contour of the rotor and the proportions for the several curves whereby the ends of the major circular arc and the minor circular arc are interconnected by curves which effect a constant rate of acceleration for one half of the movement of the coaxing abutment and a constant rate of deceleration for the second half of the movement of the abutment. The proportions have been represented in Fig. 8 and are as follows:

A =angular length of each circular arc in degrees

R =radius of major circular arc

n =the number of major arcs, or the number of minor arcs

r =radius of minor circular arc

R_m =radius at 45 degrees to a radial line bisecting either adjacent circular arc

R_L =radius at L degrees from end of major circular arc

r_L =radius at L degrees from end of minor circular arc.

The following equations govern the proportions in which the contours are formed:

$$R_m = \frac{R+r}{2}$$

$$R_L = R - \frac{R - R_m}{\left(\frac{360}{n} - A\right)^2} \cdot \frac{2L}{2L}$$

4

$$r_L = r + \frac{R - R_m}{\left(\frac{360}{n} - A\right)^2} \cdot \frac{2L}{2L}$$

$$R + r = R_L + r_L$$

I have found that mathematical formula set forth herein highly practicable in producing efficient pump and motor equipment. I realize however, that modifications may be made and I desire that it be understood that no limitation upon the invention are intended other than may be imposed by the scope of the appended claim.

The phase displacement of the rotors in series is determined by

$$\frac{360}{n} \text{ degrees}$$

I claim:

20 A device of the class described comprising a casing for fluid including a series of stator chambers, a shaft extending therethrough, a series of profiled rotors phase displaced

$$\frac{360}{n} \text{ degrees}$$

25 on said shaft, there being one rotor to each chamber aligned with the plane of the respective chamber, a division plate between said chambers, inlet and outlet passages for directing fluid through said casing and said division plate and said chambers, diametrically disposed slidable abutments extending from the casing through the stator chambers to the exterior peripheral faces of said rotors, said rotors each having its periphery formed on an even number not less than four of equal arcs of major radius and a corresponding number of equal arcs of minor radius, each arc of major radius being joined to an adjacent arc of minor radius by a curve determined by points located according to the equations:

$$40 R_m = \frac{R+r}{2}$$

$$R_L = R - \frac{R - R_m}{\left(\frac{360}{n} - A\right)^2} \cdot \frac{2L}{2L}$$

$$r_L = r + \frac{R - R_m}{\left(\frac{360}{n} - A\right)^2} \cdot \frac{2L}{2L}$$

$$R + r = R_L + r_L$$

wherein

A =angular length of each circular arc in degrees

R =radius of major circular arc

r =radius of minor circular arc

R_m =radius at

$$\frac{360}{2n} \text{ degrees}$$

to a radial line bisecting either adjacent circular arc

R_L =radius at L degrees from end of major circular arc

r_L =radius at L degrees from end of minor circular arc

L =distance in degrees from end of major and minor circular arcs

n =number of major arcs or the number of minor arcs.
